L. A. DANCO

BOX OR SIMILAR ARTICLE

Filed Feb. 3, 1928

Leon A. Danco
Inventor

By his Attorney
James Verdi

UNITED STATES PATENT OFFICE.

LEON A. DANCO, OF ROCKVILLE CENTER, NEW YORK, ASSIGNOR TO MCKESSON & ROBBINS, INCORPORATED, OF BRIDGEPORT, CONNECTICUT, A CORPORATION OF CONNECTICUT.

DESIGN FOR A BOX OR SIMILAR ARTICLE.

Application filed February 3, 1928. Serial No. 25,142. Term of patent 14 years.

To all whom it may concern:

Be it known that I, LEON A. DANCO, a citizen of the United States, residing at Rockville Center, in the county of Nassau and State of New York, have invented a new, original, and ornamental Design for a Box or Similar Article, of which the following is a specification, reference being had to the accompanying drawing, forming part thereof.

The figure is a perspective view of my new design.

I claim:

The ornamental design for a box or similar article, substantially as shown.

LEON A. DANCO.
